No. 705,110.

Patented July 22, 1902.

E. MORITZ, L. N. FRYMIRE & S. KOONS.

RADIATOR.

(Application filed Aug. 6, 1901.)

(No Model.)

UNITED STATES PATENT OFFICE.

EMIL MORITZ, LOUIS N. FRYMIRE, AND SANFORD KOONS, OF WATSON-TOWN, PENNSYLVANIA.

RADIATOR.

SPECIFICATION forming part of Letters Patent No. 705,110, dated July 22, 1902.

Application filed August 6, 1901. Serial No. 71,099. (No model.)

To all whom it may concern:

Be it known that we, EMIL MORITZ, LOUIS N. FRYMIRE, and SANFORD KOONS, citizens of the United States, residing at Watsontown, 5 in the county of Northumberland and State of Pennsylvania, have invented a new and useful Radiator, of which the following is a specification.

This invention relates to radiators; and the 10 object of the same is to provide a simple and effective device of this class adapted for application to the smoke pipe or flue of a stove or heater and so constructed as to cause the hot air to pass into the lower end thereof 15 and as it becomes heated by the products of combustion passing into the radiator from the smoke pipe or flue will naturally rise and pass out of the upper end of the device and be immediately replaced by an incoming charge of 20 cold air, special means being provided for varying the direction of circulation of the products of combustion, so as to obtain the heat distribution as desired, whereby an economy in the use of fuel will result and an 25 apartment or inclosure become more quickly heated.

The invention consists in the construction and arrangement of the several parts, which will be more fully hereinafter described and 30 claimed.

In the drawings, Figure 1 is a side elevation of the improved radiator, showing the legs thereof broken through. Fig. 2 is a transverse vertical section of the same. Fig. 3 is 35 a horizontal section taken in a plane about centrally of the radiator.

Similar numerals of reference are employed to indicate corresponding parts in the several views.

40 The numeral 1 designates an outer cylindrical shell or casing having upper and lower removable heads 2 and 3, which are normally tied by bonding-rods 4, supplied with removable nuts 5. The heads are formed with a 45 series of openings in circular alinement and having thimbles 6 fitted in and projecting inwardly from the two heads. These thimbles form inner collars, and removably engaging the same are the upper and lower extremities 50 of vertically-disposed tubular ducts 7, which are gradually converged from their lower ends

uppermost fully to the upper ends, the thimbles of the opposite heads being proportionately sized to suit or compensate for the difference in dimension of the opposite ends of the 55 ducts. The latter are fully open at both extremities and have no communication whatever with the interior of the radiator, and centrally disposed in the latter and extending vertically therethrough is a large pipe 8 to 60 receive the smoke and products of combustion. The head 2 has a central collar 9, which fits into the upper end of the said pipe-section and also projects above the head for attachment or engagement with the smoke pipe 65 or flue of a stove or heater to which the device may be applied. The lower end of the pipe-section projects below the cap 3 for securement to the smoke pipe or flue of the stove or furnace, and at a suitable distance above the 70 lower end of the said pipe-section, but close to the lower cap or head, said section is formed with diametrically-opposed openings 10, which communicate with the interior of the radiator, and coöperating with these openings is 75 oval damper 11, secured to a damper-rod 12, which is exteriorly operative. The said damper is of such shape that when arranged in either one of two oblique positions it will shut out the one opening 10 and permit the 80 smoke and products of combustion to pass into the radiator through the other opening to thus vary the circulation, or if an unobstructed outlet of the smoke and products of combustion from the stove or furnace be desired 85 the said damper will be arranged vertically in the pipe-section 8. In planes at right angles to the opposed diametric position of the openings 10 are opposite diametrically-arranged partitions 13, which extend from the 90 bottom to a point well up in the radiator, said partitions being disposed between the section 8 and the casing 1 and serve as a baffle means for causing the smoke and products of combustion to flow upwardly through one half 95 of the radiator around the pipes in said half and then downwardly through the other half around the pipes or ducts in the latter and out through the opening 10, which communicates with the section 8 above the damper 100 which shuts said opening out of communication with the portion of the section below the

said damper. A thorough circulation of the smoke and products of combustion is thus set up, and the caloric thereof is best and most economically utilized to heat the ducts and the air contained therein, and when escape of the smoke and products of combustion is finally permitted very little, if any, heat will remain therein. To take the weight strain off the smoke pipe or flue to which the radiator is applied and to hold the radiator in stable position, legs 14 depend from the lower head or cap 3 and contact with any suitable rest below.

By having the ducts regularly converged from their lower to their upper ends the cold air will be drawn into said ducts in greater quantities at the inlet-points of the latter by the greater or less amount of suction created by the hot air flowing upwardly through and escaping from the upper reduced ends of the said ducts, the said hot air being the previous charge of cold entering the ducts and heated by the smoke and products of combustion flowing therearound within the radiator. The adjustment of the damper in either one of its two oblique positions will permit the device to be arranged to concentrate the heat more in one half than in the other in the event that one half of the radiator is disposed to receive a much colder air at one side than the other, as it is obvious that the half of the radiator that the smoke and products of combustion first enter will be more rapidly heated than the other half. The removability of the ducts is also an important feature, as in the event of wear or injury any one or more of the same may be easily removed and replaced by new ones without trouble or material delay and also without impairing the radiator as a whole. The number of ducts may be increased or decreased in proportion to the radiator structure as an entirety, and other changes in the minor details may be made without departing from the principle involved.

Having thus described the invention, what is claimed as new is—

1. In a radiator, the combination of an outer casing, upper and lower heads removably mounted therein and provided with circular lines of openings, the openings of the upper head being smaller than those of the lower head, thimbles fitted in and projecting inwardly from the openings of the said heads, vertically-disposed ducts removably engaging the inwardly-projecting thimbles and regularly converged their full lengths from the lower ends thereof to the top ends, an enlarged pipe-section vertically disposed in the

center of the radiator and fully open at both ends, the lower portion of the said pipe-section having opposite diametrically-disposed, enlarged openings, an oval damper adjustably coacting with said openings, and diametrically-disposed partitions in the radiator between the pipe-section and the casing, said partitions extending upwardly almost the full length of the radiator and dividing the latter into two halves.

2. In a radiator, the combination of an outer casing, upper and lower heads removably mounted therein, a centrally-disposed pipe-section opening through the heads and having lower openings therein and a damper, ducts vertically disposed in the casing and fully opening through the said heads, the said ducts being regularly converged their full lengths from the lower to the top ends thereof, all the ducts converging in the same direction and removably attached to said heads, and dividing-partitions in the device between the pipe-section and the casing.

3. In a radiator, the combination of an outer casing, a smoke-pipe extending through said casing and having oppositely-disposed openings in the lower end thereof, a damper disposed obliquely in the lower end of said pipe between said openings, and dividing-partitions disposed in said casing at diametrically opposite points, said partitions extending from the bottom to a point near the top of said casing.

4. In a radiator, the combination of an outer casing provided with a series of openings at its opposite ends, vertical pipes or flues disposed in said casing and adapted to register at their opposite ends with the openings in the end of said casing, dividing-partitions disposed in said casing between said pipes at diametrically opposite points, said partitions extending to a point near the top of said casing, a smoke-pipe extending through said casing and having oppositely-disposed openings in the lower end thereof, and a damper disposed obliquely in the lower end of said smoke-pipe between said openings, whereby the smoke-pipe may be alternately placed in communication with the casing on opposite sides thereof.

In testimony that we claim the foregoing as our own we have hereto affixed our signatures in the presence of two witnesses.

EMIL MORITZ.
LOUIS N. FRYMIRE.
SANFORD KOONS.
